CLAIM

The ornamental design for a toy construction block, as shown and described.

DESCRIPTION

FIG. 1 is an isometric view of a toy construction block showing my new design;

FIG. 2 is a front view thereof;

FIG. 3 is right side view thereof, the left side view being a mirror image thereof;

FIG. 4 is bottom view thereof, the top view being a mirror image thereof; and,

FIG. 5 is a rear view thereof.

The broken-line showing of environmental structure in FIG. 1 is for illustrative purposes only and forms no part of the claimed design.
